UNITED STATES PATENT OFFICE.

ALBERT H. EMERY, OF STAMFORD, CONNECTICUT.

MICROMETER-GAGE.

SPECIFICATION forming part of Letters Patent No. 361,055, dated April 12, 1887.

Application filed April 20, 1886. Serial No. 199,545. (No model.)

To all whom it may concern:

Be it known that I, ALBERT H. EMERY, a citizen of the United States, residing at Stamford, in the county of Fairfield and State of Connecticut, have invented a new and useful Improvement in Micrometer-Gages, of which the following is a specification.

The subject of this invention is a gage for taking accurate internal measurements.

10 The invention relates, first, to constructing a micrometer-gage with a handle or holding-pieces of wood or other material which is a poor conductor of heat, so that the heat from the hand may not be communicated to the metal 15 of which the gage is composed; and, further, to connecting the handle or holding-pieces to the body of the gage by pins or fastenings of a material non-conductive of heat, as hereinafter explained.

20 The invention further relates to means for adjusting the nut or screw socket on the micrometer-screw, so as to adapt the latter to work and measure with great accuracy, and to take up or compensate for any wear between 25 the parts; also, to provisions for readily fixing the gage at any measurement to which it may be set. To these ends I construct the screw-socket with a transverse slit extending on both sides of the micrometer-screw, and the set-screws by which the screw-socket is adjusted 30 to the said micrometer-screw, and I provide, in addition to said set-screws, by which the parts are kept in the required adjustment to adapt them to work accurately together, a locking- 35 screw, by which, without interfering with the set-screws, the nut or screw-socket may, when desired, be clamped upon the micrometer-screw, so as to lock the same and prevent its motion, and thus retain the gage at any adjustment to 40 which it may be set.

The invention further relates to the provision of screw-legs of different lengths, constituting the measuring-foot of the gage, interchangeable and adjustable for the purpose of accurately 45 setting the instrument at a determinate gage length while the micrometer-screw is at zero, and in connection therewith set-screws for fixing the said adjustable foot-screws at the required adjustment.

50 In the accompanying drawings, Figure I is a side view of a micrometer-gage embodying my invention. Fig. II is an end view of the

same. Fig. III is a longitudinal section thereof on the line III III, Fig. I. Fig. IV is a view of an extension-leg.

To the body 1 of the gage I attach a holding-piece or handle, 2, by means of pins 3, the handle 2 and pins 3 being made of boxwood or other material which is a poor conductor of heat, so that in using the gage its length may 60 not be materially changed by the communication of heat from the hand to the metal of which it is composed.

A deep slit, 1^a, divides the body of the gage into two parts, 4 5, the former constituting the 65 screw socket or nut of the micrometer-screw 6, and the latter a screw-socket or nut for the reception of a screw, 9, forming the foot of the gage. The longitudinal slit shown in Figs. II and III and the transverse slit 1^a (shown in 70 Figs. I and III) permit the independent contraction and expansion of the screw-sockets 4 and 5.

A cylindrical cap, 7, is screwed and riveted or otherwise permanently secured on the head 75 of the micrometer-screw, and beveled at its lower end to receive the micrometer-scale, as clearly represented in Fig. I, where it works over the primary scale shown in the same figure on the body of the gage.

The head of the gage is formed of a screw, 8, tapped into the head of the micrometer-screw, as shown in Fig. III, so that it may be readily renewed when worn. The head-screw 8 and foot-screw 9 are both of hardened steel, with 85 their faces carefully and accurately ground. The foot-screw 9 affords, as already explained, means for the setting of the instrument to a determinate gage length while the micrometer is at zero, and the said screw is fixed in its adjustment by set-screws 11, securely clamping the nut or screw-socket 5 upon it. Set-screws 10 are employed to adjust the screw-socket 4 to fit the micrometer-screw 6, which works therein. In addition to these a locking-screw, 12, is provided, having a milled head for convenience of manipulation, and employed to fix the micrometer-screw 6 immovably at any gage length or release it at will without disturbing the adjustment of the set-screws 10. 90 100

It will be apparent that after the screws 10 have been adjusted to fit the screw-socket 4 as tightly as desired to the micrometer-screw 6 the said socket may be still further contracted

by means of the thumb-screw 12 to lock the micrometer-screw 6 wherever it is set, the upper member of the split socket being temporarily carried away from the heads of the screws 10, and coming against them again when released by moving back the locking-screw 12.

For the extension of the gage to greater lengths, any desirable number of additional legs 13 are provided, said extension-legs being of different determinate lengths, to be inserted in the socket 5 in place of the foot-screw 9, and having an accurately-ground end to form the gaging-foot of the instrument.

In using the device last described the foot-screw 9 is taken out and an extension screw-leg, 13, of the required length inserted in its place in the socket 5, said extension-leg 13 being screwed in to an accurate determinate length while the micrometer-screw 6 is at zero, and there fixed by means of the set-screws 11, as already described with reference to the adjustable foot-screw 9.

The removable screw 8, forming the head of a gage for internal measurements, I have described and claimed in another application of even date herewith, numbered 199,546, and designated "Case B."

Having thus described my invention, the following is what I claim as new therein and desire to secure by Letters Patent:

30

1. A micrometer-gage having the nut or screw-socket in which the micrometer-screw works split on both sides of said screw, in combination with a screw or screws for adjusting the socket to fit the micrometer-screw, and a separate locking-screw, by which the micrometer-screw may be fixed in any position to which it is set.

2. The combination of the body 1, having sockets 4 and 5, the micrometer-screw 6, sleeve 40 or cap 7, gage-head 8, set-screws 11, and interchangeable screw-legs, substantially as and for the purpose set forth.

3. A micrometer-gage having a frame split longitudinally and transversely to provide independently-adjustable screw-sockets, separate gage-screws in said sockets, and set-screws by means of which the said gage-screws can be locked or released independently, as explained.
